Primary Examiner — Eliza Z Harvey(74) *Attorney, Agent, or Firm* — Sorell, Lenna & Schmidt, LLP; William D. Schmidt, Esq.(57) **CLAIM**

The ornamental design for an endoscope valve as shown and described.

DESCRIPTION

FIG. 1 is a perspective view of an endoscope valve; FIG. 2 is a side view of the endoscope valve; FIG. 3 is a side view of the endoscope valve; FIG. 4 is a back view of the endoscope valve; FIG. 5 is a front view of the endoscope valve; FIG. 6 is a top view of the endoscope valve; and, FIG. 7 is a bottom view of the endoscope valve. The broken lines in the figures are for illustrative purposes and form no part of the claimed design.
